CLAIM

The ornamental design for a set of speakers, as shown and described.

DESCRIPTION

FIG. 1 is a front perspective view of a first speaker of a set of speakers, showing my new design; shown separately for clarity of illustration, it being understood that the grill pattern covers the entire front area;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of a second speaker of a set of speakers, shown separately for clarity of illustration; it being understood that the grill pattern covers the entire front area;

FIG. 9 is a front elevational view thereof;

FIG. 10 is a right side elevational view thereof, the left side elevational view thereof being a mirror image;

FIG. 11 is a rear elevational view thereof;

FIG. 12 is a top plan view thereof; and,

FIG. 13 is a bottom plan view thereof.
